UNITED STATES PATENT OFFICE.

EDWIN B. NATHAN, OF NEW YORK, N. Y.

LEGGING.

1,240,082.

Specification of Letters Patent. Patented Sept. 11, 1917.

Application filed January 24, 1914. Serial No. 814,040.

To all whom it may concern:

Be it known that I, EDWIN B. NATHAN, a citizen of the United States, and a resident of New York city, in the county of 5 New York and State of New York, have invented certain new and useful Improvements in Leggings, of which the following is a specification.

This invention relates to wearing apparel, 10 particularly leggings.

One object of the invention is to provide a legging which is adjustable to various sizes and when once adjusted needs no further attention on the part of the wearer.

15 Another object is to provide an adjustable legging of this character with simple fastening means, whereby the manipulation of the legging is facilitated and the neatness of its appearance enhanced.

20 A still further object is to provide an adjustable legging of this character with a simple adjustable fastener which is extremely easy to adjust and very inexpensive to manufacture.

25 The various further objects and advantages will be more fully set forth in the detailed description and the features of novelty will be particularly pointed out in the claim.

30 In the accompanying drawing illustrating this invention,

Figure 1 is an elevation of a legging with my improved adjusting and fastening means applied thereto.

35 Fig. 2 is a fragmental section taken along line 2—2 of Fig. 1.

Fig. 3 is a fragmental detail view illustrating the upper fastening and adjusting means.

40 Fig. 4 is a perspective view illustrating in detail the novel fastener.

Fig. 5 is a fragmental sectional detailed view illustrating a modified form of adjustable fastener.

45 Fig. 6 is a plan view of the fastener illustrated in Fig. 5, detached from the legging.

Referring in detail to Figs. 1 to 4 of the drawing, the legging consists of a body portion 10 of leather or other suitable material

50 made to conform to the general shape of the calf and the ankle. At the upper end of the legging adjacent to one free edge thereof, is located an inwardly extending ball stud 11 adapted to be fastened in one

of a number of outwardly opening sockets 55 12 formed adjacent to the opposing free edge of the legging.

To securely hold the rest of the legging in adjusted position about the calf of the wearer without necessitating any adjustment 60 except when the legging is first fitted on, I provide the following means. Attached to one free edge of the body of the legging, preferably adjacent to the lower end thereof, is a strap 13 extending from its point of 65 attachment 14 at a slight angle and adapted to wind around the legging up to the point of connection of its free end with a corresponding fastener attached to the body of the legging. This fastener is preferably disposed adjacent to the free edge of the body 70 of the legging opposite to the edge to which the lower end of the strap is attached, and is preferably in the form of a hook 15 pivoted to a suitable spring clip 16 riveted or 75 otherwise attached to the body of the legging. Mating with this hook is an adjustable buckle 17 mounted upon the strap. Owing to the novel construction of this 80 buckle, it may be readily adjusted to any point upon the strap and when so adjusted it may be quickly passed over the hook 15 and readily secured at any time when the legging is put on. This buckle is formed of a metal plate having adjacent to one end 85 a slot 18, the outer wall of which is formed preferably with a plurality of teeth 19. At the intermediate point of the length of the buckle is formed an upstanding loop 20 which may be struck or drawn out of the 90 material of the plate and at the farther end of the plate a perforation 21 is formed constituting an eye which may be readily inserted over the hook 15. The strap 13 is threaded through the slot 18 and through 95 the loop 20, and the buckle adjusted to the desired position.

By reason of the bending of the strap, as it passes through the slot 18 against the edge of the wall of the slot, it is firmly clipped 100 and held in position. This is made doubly secure by the teeth 19.

When it is desired to put on the legging, the fasteners 11—12 are snapped together and then the strap 13 is wound around the 105 calf and the eye 21 of the buckle 17 is inserted over the hook 15 and the latter snapped in place. The end of the strap conceals the

hook and the larger portion of the buckle, so that the neatness of the legging is enhanced.

It will be seen that once the adjustment 5 of the buckle 21 is made to suit the size of the calf of the wearer, no further adjustment will be necessary and when the legging is put on, it is merely necessary to snap the upper fasteners together and hook the 10 buckle up. Also, when the legging is put on, the upper fastener may be quickly snapped together and then the strap can be very readily manipulated to hook the same in place. The legging can thus be put on 15 very quickly and with little effort.

In the modified form illustrated in Fig. 5, I attach to the body 30 of the legging, a strap 31 and adjustably attached to the same is an ordinary buckle 32 having a tooth 33 20 passing through one of a number of perforations in the strap. To the cross bar 34 of this buckle a tab 35 is attached in which is formed an eyelet 36 adapted to be inserted over the hook 37 attached to the contiguous 25 side of the legging. The tab together with the buckle may be adjusted upon the strap to fit the size of the calf of the wearer.

and when so adjusted, the eyelet 36 may be hooked on as in the form previously described.

Having thus described my invention, I claim as new and desire to secure by Letters Patent:

A quickly attachable and adjustable legging comprising in combination with the body portion adapted to fold over the calf, means adjacent the top of the body for snapping the top edges together at a number of points, a strap secured adjacent one edge of the body and adapted to be wound around the same, a buckle slidably mounted on the strap and having one or more teeth for engaging the same at any desired point, said buckle being formed with an eye, and a hook attached to the adjacent opposite edge of the body portion and adapted to quickly engage the eye.

Signed at New York in the county of New York and State of New York this 23rd day of January A. D. 1914.

EDWIN B. NATHAN.
